UNITED STATES PATENT OFFICE.

ANSON W. ALLEN, OF PENCOYD, PENNSYLVANIA.

PROTECTING FURNACES.

No. 918,941.

Specification of Letters Patent. Patented April 20, 1909.

Application filed March 14, 1908. Serial No. 421,132.

To all whom it may concern:

Be it known that I, ANSON W. ALLEN, a citizen of the United States of America, residing at Pencoyd, in the county of Montgomery and State of Pennsylvania, have invented a new and useful Improvement for Protecting Furnaces, of which the following is a specification, reference being had to the accompanying drawings, forming part of this 10 specification, in which—

Figure 1 is a partial longitudinal vertical section of a continuous heating furnace constructed in accordance with my invention; Figs. 2 and 3 are respectively a vertical cross-section and a partial horizontal section on the lines II—II and III—III respectively of Fig. 1; Fig. 4 is a sectional plan of a soaking pit constructed in accordance with my invention; and Fig. 5 is a vertical cross-section 20 of the same.

The object of my invention is to provide means for chilling the slag which collects in heating furnaces, in order to thereby form a protective layer covering or replacing the 25 lining or part thereof.

In carrying out my invention I provide cooling channels either in the hearth or walls, or both, thereby chilling the slag adjacent to these channels to provide a protecting 30 layer and prevent splashing of the slag.

In the drawings, referring to the form of Figs. 1 to 3, 2 represents the hearth, 3 the side walls, 4 the slag outlet, and 5 the roof of an ordinary continuous heating furnace. 35 The usual skid pipes 6 are employed, which extend from the charging end of the furnace up to the hearth 2.

With the ordinary construction, the billets drop off the end portions of the water-cooled 40 skid pipes and fall on the hearth, splashing the cinder which forms thereon. This cinder acts to cut out the hearth and side walls rapidly, and to avoid this I embed in that portion of the hearth which receives the billets, 45 cooling pipes 7. These pipes may extend through the side wall of the furnace and be connected to any suitable source of supply and outlet for continuous circulation of cooling water. I have shown the pipe as 50 U-shaped for this purpose. I have also shown the hearth as sloping toward one side so that the slag dripping from the blanks may pass out through the slag spout 8, as shown in Fig. 2. I have also shown a similar 55 cooling pipe system 9 in the bridge wall 10 of the furnace, whereby the bridge wall is

cooled to prevent its being fused by the intense heat.

In Figs. 4 and 5, I show the cooling pipes 11 arranged in the side walls 12 of a soaking 60 pit furnace in the portion adjacent to the hearth. I also show pipes 13 located in the hearth of the furnace. In this case the slag is as liable to attack the lower parts of the side walls as it is to attack the floor or hearth, 65 and consequently I protect these walls, in addition to protecting the hearth. The pipes may be arranged either in the side walls or in the floor, hearth, or both, and in all cases they act to chill the slag either by contact or convection. 70

The chilled slag forms a protective layer covering, which prevents further destruction of the walls or hearth and to some extent actually replaces the lining which may be 75 already destroyed. As more slag is formed, which forms further layers or accretions, and by regulating the chilling effect, I can regulate the thickness of the layer.

The advantages of my invention will be 80 apparent to those skilled in the art, since considerable time and expense of repairing hearths and walls is avoided. A protective layer may be formed of any desirable thickness by regulating the chilling action. 85

Many changes may be made in the form and arrangement of the cooling channels, and they may be employed in furnaces of any desirable type without departing from my invention. 90

I claim:

1. A heating furnace having a refractory hearth, cooling channels located in its side walls and hearth, arranged to chill the slag and form a protective covering for the 95 hearth, said hearth having a slope to one side and a slag discharge at the lower side of the hearth; substantially as described.

2. A heating furnace having a refractory hearth provided with transversely extending 100 cooling channels arranged to chill the slag and form a protective covering for the hearth, said hearth having a slope to one side, and a slag discharge at the lower side of the hearth, substantially as described. 105

In testimony whereof, I have hereunto set my hand.

ANSON W. ALLEN.

Witnesses:

THOMAS S. NELSON,
ANNIE I. NELSON.
